UNITED STATES PATENT OFFICE

JOHN R. BLAKESLEE, OF BROOKLYN, ASSIGNOR TO F. C. MILLS, PETER GERLACH, AND RUDOLPH P. GERLACH, OF CLEVELAND, OHIO.

IMPROVEMENT IN MACHINES FOR MAKING BOLTS, RIVETS, &c.

Specification forming part of Letters Patent No. 170,151, dated November 23, 1875; application filed October 25, 1875.

To all whom it may concern:

Be it known that I, JOHN R. BLAKESLEE, of Brooklyn, in the county of Cuyahoga and State of Ohio, have invented certain new and useful Improvements in Machines for Making Bolts, Rivets, and Coupling-Pins, of which the following is a specification:

This invention relates to certain improvements in apparatus for making rivets, carriage-coupling pins, bolts, and other similar articles, its object being to produce a machine by means of which the rivets, pins, or bolts can be turned out complete ready for the market, the cutting, heading, and pointing of the same being accomplished at one heat after the bars leave the rolls, and by means of which the rivets, pins, or bolts can be formed with either round, square, or other shaped heads in a more perfect and expeditious manner than heretofore; and my invention consists in the combination, with horizontally-arranged forming and cutting dies and a heading-die or dies, of a clamping-die for clamping and holding the bar or blank outside of the cutting and forming dies, for the purpose of leaving the end of the bar squarely cut to be presented to the action of the heading-die for the formation of the next pin or bolt, as will be more fully hereinafter described.

In the drawing, Figure 1 represents a top view of my apparatus. Fig. 2 represents a transverse vertical section on the line $x x$ of Fig. 1. Fig. 3 represents a detached view of the clamping-die; Fig. 4, a detached view of the heading-die; and Fig. 5, a detached view of the feeding-die employed in forming a square-headed bolt.

The letter A represents the frame or bed of the machine, which carries the various working parts of the same, and which is substantially made of iron or other suitable material, in order to bear the strain to which it is subjected. B represents the driving-shaft journaled near one end in the frame A, the ends projecting at each side, one end being provided with a driving-wheel, C, and cams D and E, for operating the clamping and pointing dies, and the other with the cams F and F' for operating the lever G, which gives motion to the sliding forming-die H, which works in a

recess formed in one side of the frame A for the purpose. Said lever G is provided with a friction-wheel, g, at one end working between the cams F and F', and is connected to the sliding die G' at the other by means of a link, I, being pivoted near the center to an abutment, a, at the side of the frame or bed A. K represents a stationary but removable die, provided with an opening, k, and adapted to be secured in a dovetailed recess, in the inner side of the front end of the frame A, just opposite the feed-opening, the bar or blank being fed through the opening k. The said die consists of two parts, k¹ and k², the part k² forming one jaw of the clamping-die. The other part k³ of the clamping-die is made movable, and adapted to slide in a recess formed on the inner side of the front of the frame A, and extending through the side of the same, a similarly-shaped recess being formed in the die k¹, in order to allow said jaw k³ to work closely up to the aperture k. The jaw k³ consists of a bar of metal beveled at its outer end, which sets against the similarly-beveled end of the sliding bar L, which moves in a recess on the inner side of the movable jaw of the pointing-die M, and moves in a box, N, secured to the side of the frame A. The rear end of the sliding bar L sets against the cam E on the driving-shaft, and the rear end of the movable jaw of the pointing-die against the cams D on the driving-shaft, both being pressed backward in contact with their respective cams by the spring P between the jaws of the pointing-die M. k⁴, Fig. 5, represents a die to be substituted for the part k¹ when the machine is to be employed for forming square-headed rivets or pins. Said die sets in the place of the part k¹ in such manner that its edges shall be directly in line with the upper recesses of the forming-dies, so as to not cut the bar, but allow it to be headed and cut afterward. The forming-dies G¹ and G² are provided on their adjoining faces with the recesses g¹ and g², the lower recesses of which are squared at their ends adjoining the heading-dies R and R', the upper recesses being semicircular throughout their entire length. The heading-dies are secured to a solid plunger, S, confined and adapted to slide between the sides of the frame A, being

operated by means of a pitman, T, attached to a crank of the driving-shaft B. The lower die is provided with a circular recess for forming round-headed bolts, rivets, or pins, the upper die being provided with a square or other shaped recess for forming square or other shaped heads. The letter V represents two stationary arms, attached to the respective dies G¹ and G², for clearing or throwing the bolt from said dies when completed. The pointing-die M is secured to the side of the frame A, and consists of two jaws, m and m', one of which, m, is stationary, and the other, m', movable, and actuated by the cams D on the driving-shaft of the machine. The adjacent sides of said jaws are provided with recesses, between which the points of the rivets, pins, or bolts are formed. The feed-aperture is made detachable, as shown in Fig. 5, in such manner that it can be removed and replaced from time to time when worn or injured.

The operation of my apparatus is as follows: The heated rod as it comes from the rolls is inserted through the opening k, the dies G² and G¹ being separated for the purpose. The clamping-die then closes around said bar, and the sliding die G¹ advances toward the die G², passing the aperture k and cutting off the bolt, rivet, or pin, and forcing it into the forming-recesses at the same time the heading-die advances, and is forced against the end of the bolt, upsetting the metal and forming the head. The dies G² G¹ and heading-dies then separate, and the rivet, pin, or bolt is removed

by the action of the clearing-arms dropping below, after which they are taken up and submitted to the action of the pointing-die M. The movable jaw m' of said jaw receives a reciprocating motion by means of the cams D and spring P striking repeated blows upon the ends of the rivets, bolts, or pins, which are held between the pointing recesses, the number of said blows depending upon the number of the said cams.

In forming square-headed dies the part k¹ of the die K is removed and the die k⁴ substituted in its place. The bar is then fed into the upper recesses on the forming-dies, and is clamped and headed without cutting, the bolt being cut off afterward by suitable means.

What I claim, and desire to secure by Letters Patent, is—

The combination of the horizontally-arranged forming and cutting dies, the heading-die or dies, and the clamping-die for clamping and holding the bar or blank outside of said cutting and forming dies, for the purpose of leaving the end of the bar squarely cut to be presented to the action of the heading-die for the formation of the next pin or bolt, substantially as described.

In testimony that I claim the foregoing I have hereunto set my hand in the presence of the subscribing witnesses.

JOHN R. BLAKESLEE.
